UNITED STATES PATENT OFFICE.

JULIUS ADOMAITIS, OF CHICAGO, ILLINOIS.

WINDOW SEAT.

Application filed April 9, 1925. Serial No. 21,794.

My invention relates to window-seats, the invention being more particularly related to a construction of the type designed to afford a supporting seat or platform for an individual while engaged in washing windows or engaged in making repairs on the exterior side of a building, and the paramount object of my invention is the provision of an improved construction of this character which will be highly efficient in use and economical in manufacture.

Other objects will appear hereinafter.

The invention consists in the combinations and arrangements of parts hereinafter described and claimed.

The invention will be best understood by reference to the accompanying drawings forming a part of this specification, and in which,

Fig. 1 shows a cross-section through a window-sill and frame, and also through my improved window-seat which is illustrated as applied to the sill and frame;

Fig. 2 represents a top plan view of my window-seat;

Fig. 3 shows a sectional view taken approximately on the line 3—3 of Fig. 2; and

Fig. 4 is a detailed view of a bearing plate.

With more particular reference to the accompanying drawing, wherein I have illustrated the preferred embodiment of my invention, the numeral 5 represents in general a window-seat or board to the underside of which are secured in spaced relation the supporting members 6. These supporting members extend transversely of the board as clearly shown in Fig. 2 and the same are rigidly secured to the board by screws as 7 or other equivalent means.

Also extending across the under side of the seat 5 are strip members 8, which are of such length with respect to the width of the window-seat that their extremities protrude for a short distance beyond the opposite sides 9 and 10 of the window-seat. Attached to the protruding portions of the strip members are shackles 11 which as best shown in Fig. 2 extend upwardly at the opposite sides 9 and 10 of the window-seat and embrace arms 12 which extend across the top side of the window-seat. Under this arrangement the window-seat is held between the strips 8 and the arms 12 and also between the shackles 11 which connect the strips 8 with the arms 12 at the opposite sides 9 and 10.

The arms 12 are of considerably greater length than the width of the window-seat in order that the former will extend across the members comprising the bottom of the window, for instance, the associated sills 13, 14 and 15 as illustrated in Fig. 1. The arms 12, in order to be properly adjustable for association with windows of different lengths, are normally adjustable in the shackles 11. When the necessary adjustment has been made, it is desirable to secure the arms 12 rigidly to the shackles so that they will be held fixed in relation to the window-seat. To this end, there are mounted between the connecting top bars 16 of the shackles and the top sides 17 of the arms the bearing plates 18 which are preferably mounted upon the shackle sides by being provided at their opposite ends with notches 19 receptive of the shackle sides. Threaded for adjustment through the top bars 16 of the shackles are screw elements 20 which are adapted to engage the bearing plates 18. By manipulating the screw members 20, the bearing plates 18 may be forced into tight engagement with the arms so as to hold the latter against movement relatively to the window-seat.

As illustrated in Fig. 1 the window-seat is placed in position by resting the supporting members 6 upon the top of the outer sill 13. Preferably and as shown, the bottom edges of the supporting members 6 are inclined downwardly and outwardly as at 21 in agreement with the inclination 22 of the sill 13, so that the window-seat will be supported substantially in a horizontal position. To the inner ends of the arms 12 are secured hook members 23 designed to engage over the inner edge of the inner window-sill 15, as clearly shown in Fig. 1.

While I have illustrated and described the preferred form of construction for carrying my invention into effect, this is capable of variation and modification without departing from the spirit of the invention. I, therefore, do not wish to be limited to the precise details of construction set forth, but desire to avail myself of such variations and modifications as come within the scope of the appended claims.

Having described my invention, what I claim as new and desire to secure by Letters Patent is:

1. A window-seat comprising a plate

- member, strips extending across the under side of the plate member, shackles embracing the strips and projecting above the top side of the plate member, and arms extending across the top side of the plate member, embracing by and adjustable in the shackles, substantially as described.
2. A window-seat comprising a seat member having means adapted to rest upon the window-sill, strips arranged on the under side of the seat member, arms extending across the top side of the seat member, shackles attached to said strips and embracing the arms at opposite sides of the seat member, bearing plates disposed between said arms and said shackles, and members adjustable in said shackles and adapted to engage said bearing plates for maintaining
- 5
- 10
- 15

the arms rigid with the said seat member, substantially as described.

3. In a window-seat, the combination with a seat member and a strip arranged thereon, of an arm extending across the seat member in opposed relation to the strip, shackles attached to the strip and embracing the arm at opposite sides of the seat member, bearing plates located between the arm and said shackles and having means affording a guide during the movement thereof, and means adjustable in said shackles and engaging said bearing plates for maintaining the arm rigid with said seat member, substantially as described.

In testimony whereof I have signed my name to this specification.

JULIUS ADOMAITIS.
